(57) **CLAIM**

The ornamental design for an optical disc memory, as shown and described.

DESCRIPTION

FIG. 1 is a front view of an optical disc memory showing our new design;

FIG. 2 is a top plan view thereof;

FIG. 3 is a bottom plan view thereof;

FIG. 4 is a left side view thereof;

FIG. 5 is a right side view thereof;

FIG. 6 is a rear view thereof;

FIG. 7 is a perspective view thereof; and,

FIG. 8 is a perspective view thereof in a state that a tray of the optical disc memory is drawn out.
